UNITED STATES PATENT OFFICE

LOLLE D. SCHULTZ, OF LONG BEACH, CALIFORNIA

ADJUSTABLE CHIROPRACTIC BED APPLIANCE

Application filed September 26, 1928. Serial No. 308,361.

This invention relates to an adjustable chiropractic bed appliance whereby the spring is taken out of the bed mattress so that a chiropractic adjustment can be given to a patient without removal from the bed.

An object of my invention is to provide an appliance of the character stated which can readily be transported and which can be quickly and easily placed in position.

10 A further object is to provide a chiropractic bed appliance which is readily adjustable to accommodate various beds.

Still another object is to provide an appliance of the character stated which is simple in construction, effective in use, and inexpensive to manufacture.

Other objects, advantages, and features of invention may appear from the accompanying drawing, the subjoined detailed description, and the appended claim.

In the drawing

Figure 1 is a side elevation of a bed with my appliance in position thereunder.

Figure 2 is an end view of the same.

25 Figure 3 is a fragmentary sectional view of one of the locking members.

Figure 4 is a sectional view taken on line 4, 4 of Figure 3.

Figure 5 is a side elevation of one of my 30 appliances.

Figure 6 is an end view of the same.

Referring more particularly to the drawing, the bed 1 is provided with the usual mattress 2 upon which the patient lies and as 35 previously stated it is necessary to prevent the action of the springs under the mattress so that an adjustment can be given to the patient. I accomplish this by means of a pair of adjustable and yet rigid appliances 3, each of which comprises a pair of legs 4, 5, said legs being preferably of channel iron construction, although, obviously, any suitable strong construction could be used.

40 A tube 6 is secured to one end of the leg 5 and rises substantially at right angles thereto, said tube being welded, or otherwise suitably secured to the leg. A post 7 is secured to one end of the leg 4 in the same manner as the tube 6 and this post extends substantially 45 at right angles to the leg 4. The post 7 fits

closely within the tube 6 and is slidable therein.

The post is held at various adjusted positions by means of a locking pin 8 which extends into the side of the tube 6, and a 55 spring 9 bears against the head 10 to urge said head inwardly into one of a series of notches 11 in the post 7. A square recess 12 is provided in the post 7 and when the pin 8 enters this recess the post is in collapsed position and will not move outwardly until said pin is released. During transportation from place to place the pin rests in the recess 12 and, therefore, the two legs 4, 5 cannot be accidentally spread apart. To prevent rotation of the legs 4, 5 I provide a key 13 in the tube 6 which key fits into a slot 14 in the post 7.

In operation, the two appliances 3 are pushed under the bed, the upper leg 4 resting 70 immediately under the mattress 2. The legs 4, 5 are pulled apart a sufficient distance so that the mattress will not rest upon or receive any resiliency from the springs of the bed. The appliances 3, 3 are spaced a suitable 75 distance apart under the mattress and the patient is then moved on the mattress until he rests immediately over the appliances 3, 3 and bears upon the upper leg 4. The practitioner can now readily complete the adjustment.

Having described my invention, I claim:

An adjustable chiropractic bed appliance adapted to be positioned under a bed having springs, whereby the resiliency is taken out of the springs, said appliance comprising a horizontally extending leg formed of channel iron, a tube rising from one end of said leg, a second leg formed of channel iron, a post depending from one end of said second leg, said post extending into the tube, said post and tube having key-ways formed therein, a key in said key-ways whereby relative rotation of said post and tube is prevented, a spring actuated pin extending through said tube, said post having recesses therein into which the pin extends whereby the post is adjustably held in the tube.

In testimony whereof, I affix my signature.
